(57) **CLAIM**

The ornamental design for a stackable wine tasting tray, as shown and described.

DESCRIPTION

FIG. 1 is a perspective view of a stackable wine tasting tray, showing my new design;

FIG. 2 is a top view of the stackable wine tasting tray of FIG. 1;

FIG. 3 is a bottom view of the stackable wine tasting tray of FIG. 1;

FIG. 4 is a front view of the stackable wine tasting tray of FIG. 1;

FIG. 5 is a back view of the stackable wine tasting tray of FIG. 1;

FIG. 6 is a left side view of the stackable wine tasting tray of FIG. 1;

FIG. 7 is another perspective view of the stackable wine tasting tray as shown in FIG. 1;

FIG. 8 is a cross-sectional front view of the stackable wine tasting tray as shown in FIG. 7, taken along line 8-8;

FIG. 9 is another cross-sectional front view of the stackable wine tasting tray as shown in FIG. 7, taken along line 9-9;

FIG. 10 is a front view showing two stackable wine tasting trays, as shown in FIG. 1, stacked on top of one another;

FIG. 11 is a front cross-sectional view showing two stackable wine tasting trays stacked on top of one another, as shown in FIG. 10;

FIG. 12 is a perspective view of a stackable wine tasting tray, showing my new design;

FIG. 13 is a top view of the stackable wine tasting tray of FIG. 12;

FIG. 14 is a bottom view of the stackable wine tasting tray of FIG. 12;

FIG. 15 is a front view of the stackable wine tasting tray of FIG. 12;

FIG. 16 is a back view of the stackable wine tasting tray of FIG. 12;

FIG. 17 is a left side view of the stackable wine tasting tray of FIG. 12;

FIG. 18 is another perspective view of the stackable wine tasting tray as shown in FIG. 12;

FIG. 19 is a cross-sectional front view of the stackable wine tasting tray as shown in FIG. 18, along line 19-19;

FIG. 20 is another cross-sectional front view of the stackable wine tasting tray as shown in FIG. 18, along line 20-20;

FIG. 21 is a front view showing two stackable wine tasting trays, as shown in FIG. 12, stacked on top of one another; and,

(Continued)

FIG. 22 is a front cross-sectional view showing two stackable wine tasting trays stacked on top of one another, as shown in FIG. 21.

The right side views are identical to the left side views and are therefore omitted. The broken lines shown in FIGS. 1, 2, 7-13, and 18-22 form no part of the claimed design.
